(57) **CLAIM**

The ornamental design for forked ends, as shown and described.

DESCRIPTION

FIG. 1 is a top perspective view of forked ends showing my new design;

FIG. 2 is a front side elevational view thereof;

FIG. 2A is an enlarged perspective view of a feature thereof shown in FIG. 2;

FIG. 3 is a rear side elevational view thereof;

FIG. 4 is a right side elevational view thereof, the left side elevational view being a mirror image of the right side; and, FIG. 5 is a bottom plan view thereof.

It is noted that any broken line illustration of environmental structure in the drawing is not part of the claimed design.
